(57) **CLAIM**

The ornamental design for a patient monitor, as shown and described.

DESCRIPTION

FIG. 1 is a perspective view of a patient monitor embodying our new design;

FIG. 2 is another perspective view thereof;

FIG. 3 is top view thereof;

FIG. 4 is bottom view thereof;

FIG. 5 is a side view thereof;

FIG. 6 is another side view thereof;

FIG. 7 is a front view thereof;

FIG. 8 is a back view thereof;

FIG. 9 is a perspective view thereof in a condition of use; and,

FIG. 10 is a perspective view thereof in another condition of use.

The broken lines illustrate portions of the patient monitor that form no part of the claimed design, and the additional broken lines in FIGS. 9 and 10 represent environmental subject matter; the broken lines form no part of the claimed design.
